UNITED STATES PATENT OFFICE.

WILLIAM E. THOMAS, OF FORD'S STORE, MARYLAND.

IMPROVEMENT IN PENCIL-CASE ATTACHMENTS TO SLATES.

Specification forming part of Letters Patent No. 177,589, dated May 16, 1876; application filed March 20, 1876.

To all whom it may concern:

Be it known that I, WILLIAM E. THOMAS, of Ford's Store, in the county of Queen Anne and State of Maryland, have invented a new and Improved Pencil-Case Attachment to Slates; and I do hereby declare that the following is a full, clear, and exact description of the same.

The invention is an improvement in the class of pencil-case attachments for frames of drawing-slates which consist of a tube pivoted at one end in a recess or cavity of the frame.

The improvement relates to an attachment formed of a tube open at each end, and hinged on the side to a rod, which spans the recess in the frame, whereby, when the tube is closed, it is held by friction of its side with the side wall of said recess, as hereinafter described.

In the accompanying drawing, forming part of this specification, Figure 1 represents a plan view of a slate provided with my improvement, and Fig. 2 is a cross-section on line xx of Fig. 1.

The pencil-tube A may be made of various forms or materials; but it is preferably cylindrical, and may be cheaply constructed of tin or other light sheet metal. One of the bars B of the slate-frame is cut away to form a longitudinal recess, C, to receive the tube, and a rod, D, is secured to the said bar in such manner as to span or bridge the same lengthwise. The tube A is connected to the rod D by a hinge-joint, so that it may be turned thereon. It is open at each end, to permit convenient insertion and removal of the pencil, and the latter is held in the tube while in the recess C by reason of the ends of the tube abutting the end walls of the recess, as shown. The tube

is itself held in the recess by friction between their respective sides, which come in contact; but it is apparent that for this result the tube must be of such diameter as to fit tightly between the rod D and longer side of the recess. In other words, the degree of friction corresponds to the pressure of the rod on the tube. It is likewise obvious that if at any time the friction should become too slight to hold the tube in place, the difficulty may be removed by bending the road inward, to cause it to press more firmly on the tube.

When it is desired to remove a pencil from the tube, it is requisite, or at least the most convenient method, to tilt the slate-frame, thus causing the pencil to slide out at that end of the tube which is lowest.

This attachment does not perceptibly weaken the slate-frame, nor increase the size or bulk of the same, nor add materially to the first cost of the slate, while it constitutes a safe repository for pencils, which is always convenient of access.

What I claim is—

The pencil-tube open at each end, and hinged on the side to the rod spanning the recess in the frame, as shown and described, whereby it is adapted to turn laterally on said rod, and be held by friction produced by the pressure of said rod, in the manner specified.

The above specification of my invention signed by me this 9th day of March, A. D. 1876.

W. E. THOMAS.
